CAR ROOF JOINT

John M. Rudel, Montreal, Quebec, Canada, assignor to Standard Railway Equipment Manufacturing Co. (Canada) Limited, Montreal, Quebec, Canada, a corporation of the Dominion of Canada

Application January 13, 1945; Serial No. 572,681
In Canada October 14, 1944

27 Claims. (Cl. 108—54)

1
Introduction

In the construction of a railway car roof, the principal objectives are to provide a structure which is light, flexible to a suitable degree and in the right directions, has adequate load bearing capacity and is sufficiently strong to withstand extreme stresses exerted by the car movements. In the accomplishment of these objectives, many different types of structure have been developed.

To give the roof sheets adequate load bearing capacity, these structures have employed stiffening ribs, bulges, or other protuberances of various shapes. To further this capacity, special joints between the sheets have been used, which are designed to take up the stresses to which the sheets themselves are subjected.

Objects

Having regard to the foregoing, objects of the present invention are to provide an improved car roof structure, an improved joint which may be used with existing car roof structures and a roof in which the elements are relatively simple and easy to fabricate and to assemble.

Structure

With these and other objects in view, the applicant's improved roof embodies a special joint in which the margins of the respective roof sheets are securely held together by a carline of special construction. Broadly, according to this construction, the adjacent margins of the respective roof sheets which are generally made of galvanized sheet, are juxtaposed. Reinforcing members of non-galvanized metal shroud the juxtaposed marginal portions of the adjacent sheets and a seam weld connects the shroud members and marginal portions of the sheets remotely from the marginal edges of the sheets. According to one embodiment of the invention, a shroud member is provided for the margin of each sheet, the respective shrouding members being butted together and welded. The members shroud the sheets at top and bottom. According to another construction, a common shrouding member is provided for the abutting marginal portions at top and bottom thereof and these shrouding members are welded to the sheets. The structure described, permits a weld being made without disintegrating the marginal portions of the sheets, as for instance, by removing the galvanizing. It also keeps the galvanizing from clogging up the rollers on the seam welder. Having parent metal on each side of the

2

sheet affords the advantage of getting a better joint which is more cohesive and does not allow rust to form on the sheets.

Since joints of this kind are particularly applicable for use with the type of roof described in the applicant's U. S. Patent No. 2,241,738, their application to a roof of this type will now be described by way of example and by reference to the accompanying drawings, in which,

10 Figure 1 is a plan view of a railway car roof constructed according to this preferred construction one form of joint according to this invention forming a part thereof.

Figure 2 is an enlarged cross section along the line 2—2 of Figure 1.

15 Figure 3 is an enlarged fragmentary vertical cross section of one form of joint or carline according to the invention.

20 Figures 4 to 9 are enlarged fragmentary vertical cross sections of other forms of carlines according to the invention.

Detailed description

25 Referring more particularly to the drawings, the car roof A is of the radially arched type, constructed of a series of metal roof sheets 10 preferably of the special form described in the patent referred to above and usually made of galvanized iron sheet.

30 The roof sheets are inter-connected at their adjacent edges by the new joints 11 to be described in detail and extending from one side of the car to the other. The sheets are attached to the car by conventional means as for instance, integral eaves flanges 12 secured to the side plates 13 of the car.

The sheets are specially formed with a bulge 20 of constant width taking in the major portion of the width of the sheet, and whose cross 40 section is a shallow arc increasing in height and in curvature from adjacent the eaves flanges to adjacent the centre line of the roof substantially as indicated in the figures. Adjacent to the sides of the sheet this bulge merges into a side portion curved in cross section oppositely to the bulge 20 and terminating in a more or less flat marginal portion 21 adapted to be joined to the next roof sheet.

45 Preferably, the arcs of curvature of the bulge 50 and that of the side portions are substantially equal and tangential to one another. Unlike most prior art structures, the sheets are nowhere bent to an angle or a curve sufficiently acute to distort the metal to a degree at which it might fatigue and eventually rupture. Sur-

prisingly, however, despite the teachings of the prior art that most extreme protuberances of the sheet are necessary for making the roof self-supporting, the present simple structure fulfills its purpose admirably by giving the roof remarkable strength and at the same time the necessary flexibility required to achieve durability. In addition, the less pronounced bulge of the roof sheet is easier to fabricate than some of the more extreme forms of protuberances.

According to the present invention, the adjacent marginal portions 21 of the respective sheets are connected together by a special joint running the width of the roof as will be described in its various modifications.

Referring to Figure 3, this joint includes a clip B made of ungalvanized metal and having portions 30 and 31 overlying and underlying the edge of the sheet respectively, and a sloping portion 32 disposed towards the adjacent clip. The joint is completed by a fillet weld 35 which is laid in the V formed between the two clips. A seam weld 36 extends through the portions 30 and 31 and the marginal portion 21 of each sheet. Thus each clip runs the entire width of the sheet and is securely fastened to the marginal portions thereof. The clips are securely fastened to one another, completing the joint.

Figure 4 illustrates another form of joint in which a clip C is employed. This clip is different in construction to the clip B in that the upper portion 40 has the conformation indicated so that the edge of the clip has a vertical face 47 which is juxtaposed to a similar face on the adjacent clip and a diagonal face 48. A V-shaped channel is formed between the faces 48 of the respective clips. A fillet weld 45 is laid in the channel. Similarly to the joint illustrated in Figure 3 a seam weld 46 secures the upper and lower portions of the clip and the marginal portion 21 of the sheet together.

Figure 5 illustrates another form of joint in which a substantially L-shaped clip is employed having upper and lower portions 50 and 51, adapted respectively to overlie and underlie the marginal portion 21 of its sheet. The clip is provided with an upstanding portion 57 adapted to abut the similar portion of the adjacent clip and having a diagonal edge 52 adapted to form with a similar edge on the adjacent clip a channel to receive a fillet weld 55. A seam weld 56 joins the upper portion 50 and 51 to the marginal portion 21 of the sheet.

Figure 6 illustrates still another form of joint in which the marginal portions are held together by reinforcing members 60 and 61 which overlie and underlie them respectively. Seam welds 62 and 63 join the marginal portions 21 to the reinforcing members 60 and 61.

Figure 7 illustrates another form of joint in which the edges 21 of the roof sheets are bent over and hooked together as indicated. The upper reinforcing member 70 is domed as at 75 so as to house the joined ends of the sheets 21. The upper and lower reinforcing members 70 and 71 are also seam welded to marginal portions of the sheets as at 72.

Figure 8 illustrates a form of joint similar to that illustrated in Figure 6 including an upper reinforcing member 80, and a lower reinforcing member 81. In this case, the upper member 80 is provided with an upstanding flange 81.

Figure 9 illustrates a form of joint comparable to that shown in Figure 6 but differing in that the upper reinforcing member is provided with

a dome 95 adapted to receive upturned ends 21 of the roof sheets, which are juxtaposed as indicated. A weld 97 joins the ends 21 of the sheets and the member 95 together. Seam welds 92 also join the upper and lower reinforcing members to each other and to the marginal portions of the roof sheets.

As shown in Figure 2 a running board 16 may be secured to the joint by angle irons saddle 17 which are butted into the weld 15.

Advantages

Various advantages of the invention will become evident from a study of the above description. Principal among these are the provision of strong, attractive joints which can be formed by welding without disintegration of the galvanizing of the roof sheets at unprotected points.

It will be understood that, without departing from the spirit of the invention or the scope of the claims, various modifications may be made in the specific expedients described. The latter are illustrative only and not offered in a restricting sense, it being desired that only such limitations shall be placed thereon as may be required by the state of the prior art.

I claim:

1. In a railway car roof of the type in which marginal portions of adjacent metal sheets are joined together, a joint including a clip having a part overlying and a part underlying the marginal portion of each sheet and a portion abutting that of the clip of the adjacent sheet, the abutting portions of abutting clips each having a diagonally sloping edge forming therebetween a channel, a fillet weld in the channel securing the clips together; and a common seam weld joining together the overlying and underlying parts of each clip and its respective marginal portion.

2. In a railway car roof of the type in which marginal portions of adjacent metal sheets are joined together, a joint, as described in claim 1, wherein the abutting faces of each clip are vertical and the diagonal face of the clip is formed by a domed portion of the overlying part.

3. In a railway car roof of the type in which marginal portions of adjacent metal sheets are joined together, a joint, as claimed in claim 1, wherein the abutting portions of each clip are formed by relatively elongated vertical sections extending upwards from the overlying part, and the diagonally sloping edge is formed on the top of the vertical section.

4. In a railway car roof of the type in which marginal portions of adjacent metal sheets are joined together, a joint, comprising, a common member overlying the marginal portions of adjacent sheets, a common member underlying the marginal portions of adjacent sheets, and a common seam weld joining together the marginal portions of each sheet to the overlying and underlying members respectively.

5. In a railway car roof, a joint as claimed in claim 4, wherein the upper member is domed, the edges of the sheets are interlocked, and the marginal portions are seam welded to the overlying and underlying members respectively.

6. In a railway car roof, a joint as claimed in claim 4, wherein the overlying member is provided with a centrally located upwardly extending flange.

7. In a railway car roof, a joint as claimed in claim 4, wherein the upper member is domed, the edges of the sheets are interlocked, and the mar-

ginal portions are connected to overlying and underlying members respectively.

8. In a railway car roof, a joint as claimed in claim 4, wherein the overlying member is provided with a centrally located upwardly extending channel, the marginal portions of adjacent sheets being upturned juxtaposed and housed within said channel, a seam weld joining together the upturned portions of the edges and the overlying member, a seam weld joining the flat portions of the overlying member and the underlying member respectively with the margins of the sheet.

9. In a railway car roof of the type in which marginal portions of adjacent metal sheets are joined together, a joint including a clip having a part overlying and a part underlying the marginal portion of each sheet and a portion abutting that of the clip of the adjacent sheet, the abutting portions of abutting clips each having a diagonally sloping edge forming therebetween a channel, a fillet weld in the channel securing the clips together, and means joining together the overlying and underlying parts of each clip and its respective marginal portion.

10. In a railway car roof of the type in which marginal portions of adjacent metal sheets are joined together, a joint, as described in claim 9, wherein the abutting faces of each clip are vertical and the diagonal face of the clip is formed by a domed portion of the overlying part.

11. In a railway car roof of the type in which marginal portions of adjacent metal sheets are joined together, a joint, as claimed in claim 9, wherein the abutting portions of each clip are formed by relatively elongated vertical sections extending upwards from the overlying part, and the diagonally sloping edge is formed on the top of the vertical section.

12. In a structure of the type in which marginal portions of adjacent metal sheets are connected by a joint, the joint including shrouding means overlying said marginal portions and shrouding means underlying said marginal portions, said shrouding means masking the edges of the sheets, and a seam weld between each sheet and the overlying and underlying shrouding means remote from said edges and remote from the outer sides of said shrouding means.

13. A structure as defined in claim 12 wherein the metal sheets are galvanized and whereby the welded portions of the galvanized sheets are protected by said shrouding means.

14. In a structure in which the margins of metallic sheets are joined together; a joint including an upper part overlying the margins of adjacent sheets and a lower part underlying the margins of adjacent sheets, and seam welds remote from the outer sides of said parts joining together the margin of each sheet, respectively, to said overlying and underlying parts, whereby the edges of the metallic sheets and the welded portion of each sheet is protected.

15. In a structure in which the margins of galvanized metallic sheets are joined together; a joint including an upper part overlying the margins of adjacent sheets and a lower part underlying the margins of adjacent sheets, and seam welds remote from the outer sides of said parts joining together the margin of each sheet, respectively, to said overlying and underlying parts, whereby the edges of the metallic sheets and the galvanization around the welded portion of each sheet is protected.

16. In a structure of the type in which mar-

ginal portions of adjacent metal sheets are joined together, a joint including a clip having a part overlying and a part underlying the marginal portion of each sheet and a portion abutting that of the clip of the adjacent sheet, the abutting portions of abutting clips each having a diagonally sloping edge forming therebetween a channel, a fillet weld in the channel securing the clips together, and a common seam weld joining together the overlying and underlying parts of each clip and its respective marginal portion.

17. In a structure of the type in which marginal portions of adjacent metal sheets are joined together, a joint, as described in claim 16, wherein the abutting faces of each clip are vertical and the diagonal face of the clip is formed by a domed portion of the overlying part.

18. In a structure of the type in which marginal portions of adjacent metal sheets are joined together, a joint, as claimed in claim 16, wherein the abutting portions of each clip are formed by relatively elongated vertical sections extending upwards from the overlying part, and the diagonally sloping edge is formed on the top of the vertical section.

19. In a structure of the type in which marginal portions of adjacent metal sheets are joined together, a joint including a clip having a part overlying and a part underlying the marginal portion of each sheet and a portion abutting that of the clip of the adjacent sheet, the abutting portions of abutting clips each having a diagonally sloping edge forming therebetween a channel, a fillet weld in the channel securing the clips together, and means joining together the overlying and underlying parts of each clip and its respective marginal portion.

20. In a structure of the type in which marginal portions of adjacent metal sheets are joined together, a joint, as described in claim 19, wherein the abutting faces of each clip are vertical and the diagonal face of the clip is formed by a domed portion of the overlying part.

21. In a structure of the type in which marginal portions of adjacent metal sheets are joined together, a joint, as claimed in claim 19, wherein the abutting portions of each clip are formed by relatively elongated vertical sections extending upwards from the overlying part, and the diagonally sloping edge is formed on the top of the vertical section.

22. In a structure in which the marginal portions of adjacent galvanized metallic sheets are secured together, a joint comprising a common member overlying said marginal portions, a common member underlying said marginal portions, and a common seam weld joining together the overlying and underlying portions and each member and its respective sheet marginal portion, whereby the welded portions of the galvanized sheets are protected by said members.

23. In a structure in which the marginal portions of adjacent metallic sheets are joined together, a joint including a clip having a part overlying and a part underlying the marginal portion of each sheet and a portion abutting that of a clip of the adjacent sheet, said abutting portions formed to provide a common groove for the reception of welded material to join said clips together, and a common weld joining together the overlying and underlying parts of each clip and its respective marginal portion.

24. In a structure in which the marginal portions of adjacent galvanized metallic sheets are joined together, a joint including a clip having

a part overlying and a part underlying the marginal portion of each sheet and a portion abutting that of a clip of the adjacent sheet, said abutting portions formed to provide a common groove for the reception of welded material to join said clips together, and a common weld joining together the overlying and underlying parts of each clip and its respective marginal portion, whereby the welded portions of the galvanized sheets are protected by said clips.

25. A structure as defined in claim 1 wherein a running board saddle is secured to said clips by said fillet weld.

26. A roof for a railway car comprising a plurality of metallic sheets adapted to extend between the side walls of a car when applied thereto, some of said sheets formed with a bulge taking the major portion of the width of the sheets whose cross section is a shallow arc increasing in height and curvature from adjacent the ends of the sheet to the center of the sheet, the opposite sides of said bulge merging into the opposite side marginal portions of the sheet upon arcs oppositely disposed to the arcs of the bulge, and means to secure the marginal portions of adjacent sheets together, said means comprising a clip having a part overlying and a part underlying the marginal portion of each sheet and a common weld joining together the overlying and underlying parts of each clip to its respective sheet marginal portion, each of said clips provided with

5

10

15

20

25

30

an abutting portion engaging the abutting portion of the adjacent clip, said clips formed to provide a common groove, and a fillet weld in said groove securing the clips together.

27. A roof for a railway car comprising a plurality of metallic sheets adapted to extend between the side walls of a car when applied thereto, some of said sheets formed with a bulge taking the major portion of the width of the sheets whose cross section is a shallow arc increasing in height and curvature from adjacent the ends of the sheet to the center of the sheet, the opposite sides of said bulge merging into the opposite side marginal portions of the sheet upon arcs oppositely disposed to the arcs of the bulge, the marginal portions of adjacent sheets being in substantially the same plane, and means to secure the marginal portions of adjacent sheets together, said means comprising a clip having a part overlying and a part underlying the marginal portion of each sheet and a common weld joining together the overlying and underlying parts of each clip to its respective sheet marginal portion, each of said clips provided with an abutting portion engaging the abutting portion of the adjacent clip substantially in the plane of the adjacent sheet marginal portions, said clips formed to provide a common groove, and a fillet weld in said groove securing the clips together.

J. M. RUDEL.
